UNITED STATES PATENT OFFICE.

PETER SAMES, OF ROCKFORD, ILLINOIS.

IMPROVEMENT IN AUTOMATIC GATES.

Specification forming part of Letters Patent No. **179,225**, dated June 27, 1876; application filed September 27, 1875.

To all whom it may concern:

Be it known that I, PETER SAMES, of the city of Rockford, State of Illinois, have invented certain Improvements in Gates, of which the following is a specification:

My invention relates to that class of gates usually known as "automatic," which can be opened and closed from both sides; and consists in the devices and combinations of devices which I now proceed to describe.

In the drawings, Figure 1 is an isometrical elevation of a gate embodying my invention; and Fig. 2 is an isometrical horizontal section of the hanging-post and hanging-stile, cut at the center of the lower hinge.

The gate is composed of rails *a*, gained into the latching-stile *b* and hanging-stile *c*, to which they are secured in any suitable manner, and is also provided with a bracing-rail, *d*, placed diagonally across the rails *a*, between the stiles *b* and *c*, and secured in place in any proper manner. The free end of the gate is provided with a lever latch-bar, *h*, of ordinary construction, fitted to engage the strike-catch *i*, secured to the latching-post *B*. *A* is a hanging-post, and *B* the latching-post, both of which may be secured in place in any suitable manner. The gate is hung to the post *A*, near its upper end, by a hook-and-eye hinge of the usual construction, and is also hung, near the lower end of the hanging-stile *c*, to the post *A*, by a hook-and-eye hinge of the peculiar construction shown in Fig. 2, in which *e* is the hook, of the usual form, and *f* is the eye which receives the hook *e*, and is of oblong form, the transverse axis of which is oblique to its shank, and is placed in the hanging-stile horizontally, on an angle of about forty-five degrees with the rear face of the hanging-stile, in such a manner that the gate, when at rest or swinging, will be in a vertical position, with the end of the oblong eye *f* toward the gate, resting against the hook *e*; and if, by any means, the lower end of the hanging-stile *c* is forced in the direction to cause the oblong eye *f* to slide on the hook *e* toward the outer end of the oblong eye, the free or latching end of the gate will be made to rise and disengage it from the strike-catch *i*.

C is an angle-lever, secured to the hanging-stile *c*, and extends below the gate, with the angle-arm *g* extending to the closing side at an angle of about forty-five degrees with the lengthwise line of the gate, and is provided with an upward-projecting stud, *k*, which receives the end of bars *D*, the other ends of which are connected to hand-levers *E*, placed one on each side of the gate at any suitable distance, and are held on fulcrum-supports on box *F*, which is designed as a protection to the parts inclosed in it; and the box may be placed under ground, if desired.

By this construction I am enabled to dispense with the high posts usually employed in the construction of automatic gates; and by means of the levers *E* and their connection with the gate I am enabled to operate the gate without dismounting or leaving the seat in the carriage, the action being as follows: The movement of the levers *E* in the proper direction will cause the lower end of the hanging-stile *c* to move obliquely toward the opening side, and the oblique oblong eye *f*, sliding on the hook *e*, will also cause the front end of the gate to rise and disengage it from the strike-catch *i*, and the continued movement of the lever will cause the gate to open, and the reverse movement of the levers will close the gate.

I claim as my invention—

1. The hand-levers *E*, connecting rods *D*, lever arm or crank *C*, in combination with the gate *A'*, with its lower hinge formed by the hook *e* and eye *f*, substantially as and for the purposes described.

2. In a self-closing gate, where the outer end has to rise to release the latch, or fall to engage the latch with the catch, the combination of the hook *e*, an oblong eye, *f*, that is oblique to its shank, with the swinging gate *A'*, constructed and operating substantially as described.

PETER SAMES.
